A. W. CARMICHAEL.
APPARATUS FOR THE MANUFACTURE OF ROSIN SOAP AND THE LIKE.
APPLICATION FILED JAN. 8, 1908.

909,058.

Patented Jan. 5, 1909.

UNITED STATES PATENT OFFICE.

ANDERSON WILLIAM CARMICHAEL, OF SAVANNAH, GEORGIA.

APPARATUS FOR THE MANUFACTURE OF ROSIN SOAP AND THE LIKE.

No. 909,058.

Specification of Letters Patent.

Patented Jan. 5, 1909.

Original application filed October 16, 1907, Serial No. 897,652. Divided and this application filed January 8, 1908.
Serial No. 409,865.

To all whom it may concern:

Be it known that I, ANDERSON W. CARMICHAEL, a citizen of the United States, and a resident of Savannah, in the county of 5 Chatham and State of Georgia, have invented a new and Improved Apparatus for the Manufacture of Rosin Soap and the Like, of which the following is a full, clear, and exact description.

10 This invention is an improved apparatus for dehydrating a saponified solution of rosin, commonly called "wet pulpy size," in the production of hard rosin soap, which is more especially used by paper mills in the so-called 15 sizing or waterproofing process.

Prior to my invention, the manufacture of rosin soap without the use of an excess of soda or carbonate of soda has been confined to soft soap containing from forty to sixty 20 per cent. or more, of water. This soap necessarily has to be packed in the better class of hard wood and waterproof barrels, whereas the soap produced by my apparatus permits of its shipment in a condensed state in cheap 25 pine wood boxes or barrels in which the rosin has been and is still being shipped, in addition to offering a considerable saving in freight, as substantially no water is transported.

Reference is to be had to the accompanying 30 drawings forming a part of this specification, in which similar characters of reference indicate corresponding parts in both views.

Figure 1 is a vertical central sectional view through an apparatus embodying my 35 invention for the production of hard rosin soap and the like; and Fig. 2 is a plan of the same.

An apparatus constructed in accordance 40 with my invention comprises a cooking vessel 5 of suitable capacity, preferably of cylindrical form and surrounded by a steam jacket 6, the latter being provided with a steam supply 7. Journalized in the center of 45 the vessel is a vertical shaft 8, having affixed thereto slightly below the top of the vessel, a series of radiating arms or blades providing a beater 9, and also with a pulley or other suitable driving means 10, fixed above the 50 beater.

Connecting with the bottom of the vessel

5 through a pipe 11, is a rotary pump 12 which discharges through a pipe 13, having the discharge end thereof overhanging the vessel above the beater 9. The apparatus is 55 also preferably provided with a supply pipe 14, for introducing the size into the vessel.

A mixture of certain proportions of rosin in its crude state, and alkali, is introduced into the vessel and brought to the state of 60 saponification by the steam in the steam jacket. To this is added the usual proportion of water, and is commonly known as "wet pulpy size," which is used for the so-called sizing or waterproofing process by mills 65 which produce paper. When the size has been consistently heated to the point where it starts to foam the foam beater 9 is set in action, beating down the foam as it rises, keeping it from running over the top and to 70 waste, and thus liberating the vapor; at the same time the rotary pump 12 is started and pumps the size from the bottom of the tank through the outlet or discharge pipe 11 and discharges the size into the top of the tank 75 above the beater, thereby providing a continuous flow from the bottom to the surface of the liquid, which facilitates the evaporation of the water. This operation is continued until substantially no water remains, 80 when the resulting product on cooling will be found to be a hard rosin soap or size of superior quality, entirely uniform in strength, purity and solubility.

Having thus described my invention, I 85 claim as new and desire to secure by Letters Patent:

1. In an apparatus of the character described, a vessel adapted to have heat applied thereto, a foam beater revolubly mounted in said vessel near the top thereof, and means for withdrawing a solution contained in the vessel from the bottom thereof and discharging it therein at the top.

2. In an apparatus of the character described, a vessel having a steam jacket, a foam beater revolubly mounted in the vessel near the top thereof, and means for pumping a solution from the bottom of the vessel and discharging it therein above said beater.

3. An apparatus of the character described, comprising a vessel adapted to con-

tain a solution for the manufacture of soap and to have heat applied thereto, a foam beater mounted in the vessel above the normal level of the solution, and means for 5 withdrawing the solution from the bottom of the vessel and discharging at the top thereof over the beater.

In testimony whereof I have signed my name to this specification in the presence of two subscribing witnesses.

ANDERSON WILLIAM CARMICHAEL.
